(57) **CLAIM**

The ornamental design for a hand-held showerhead, as shown and described.

DESCRIPTION

FIG. 1 is a front and bottom perspective view of a hand-held showerhead showing our new design;

FIG. 2 is a front view thereof;

FIG. 3 is a left side elevational view thereof; the right side elevational view being a mirror image thereof;

FIG. 4 is a top plan view thereof; and,

FIG. 5 is a bottom plan view thereof.

The broken lines in the figures are for the purpose of illustrating portions of the hand-held showerhead that form no part of the claimed design.
